VACUUM CUP

Alexander T. Koppe, Chicago, Ill.

Application May 23, 1932, Serial No. 612,988

6 Claims. (Cl. 294—64)

This invention relates to improvements in vacuum cups and its purpose is to provide a device for holding sheets of paper or the like in printing presses or other apparatus where it is desired to move a sheet of paper or other thin objects from one position to another. In printing presses and other machines of that character, it is the common practice to employ vacuum cups which are brought into engagement with the paper sheets or the like with the result that the suction which is exerted through the cup operates to cause the sheet of paper to adhere to the contacting portion of the cup and to remain in that position until the suction is released when the cup is in a new position. Devices of this character which have heretofore been provided have not been sufficiently sensitive to operate upon sheets of all thicknesses which are met with in commercial practice and they have usually been rather large and cumbersome structures which could not be used in all locations.

The principal object of the present invention is to provide an improved form of vacuum cup which will be very simple in construction and sensitive in operation so that it may be readily employed in various locations for operation upon sheets of various material and thickness. Another object of the invention is to provide an improved vacuum cup comprising relatively movable parts, one of which is adapted to be brought into engagement with the paper sheets and to yield when that engagement is effected so that a uniform contact of the periphery of the cup with the sheet is effected. A further object of the invention is to provide an improved vacuum cup in which the use of a rubber or other resilient cup member is eliminated. Still another object of the invention is to provide a vacuum cup provided with means extending across the orifice leading to the vacuum channel so that the paper sheet is not drawn into the cup by the vacuum. Other objects relate to various features of construction and arrangement which will appear more fully hereinafter.

The nature of the invention will be understood from the following specification taken with the accompanying drawings, in which three embodiments are illustrated. In the drawings,

Fig. 1 shows a vertical section through one form of the improved vacuum cup and a suction pipe by which it is carried, showing the cup proper in position to engage the uppermost sheet of a stack;

Fig. 2 is a sectional view similar to that of Fig. 1, showing the relative positions of the parts of

the device after the uppermost sheet has been engaged by the cup;

Fig. 3 shows a bottom plan view of the vacuum cup illustrated in Fig. 1;

Fig. 4 shows a vertical section through another form of the invention applied to a suction pipe, illustrating the cup in position to engage the uppermost sheet of a stack;

Fig. 5 is a sectional view similar to that of Fig. 4, showing the relative positions of the parts after the uppermost sheet of the stack has been lifted thereby;

Fig. 6 shows a bottom plan view of the device illustrated in Figs. 4 and 5;

Fig. 7 is a vertical section through the lower portion of a third form of the invention in which means are provided for preventing the paper sheet from being drawn into the vacuum channel; and

Fig. 8 is a bottom plan view of the device illustrated in Fig. 7.

As illustrated in Figs. 1, 2 and 3 of the drawings, the invention is applied to a vacuum pipe or tube 10 which may be a part of a printing press or the like and which is connected to a source of suction. This pipe is ordinarily movable so that a vacuum cup carried thereby may be brought into engagement with a pile of sheets or the sheets may be movable with their support for the purpose of bringing one sheet into engagement with the cup. The pipe 10 is provided on its under side with a circular aperture which is threadedly engaged by a hollow stem 11 upon which there is slidably mounted a cylinder 12. The lower end of the stem 11 is internally threaded and is engaged by a threaded retaining member 13 having an aperture 13^a therethrough concentric with the wall of the tube of the stem 11 and having an annular flange 13^b which extends outwardly beyond the outer surface of the stem to engage an annular internal shoulder 14 which is formed upon the inner wall of the cylinder 12. The flange 13^b of the plug 13 limits the downward movement of the cylinder under the influence of gravity.

The lower end of the cylinder 12 is internally threaded and is engaged by a head 16 having an upwardly extending externally threaded sleeve portion 16^a which engages the threads of the lower part of the cylinder, and an outwardly directed flange portion 16^b which engages the lower end of the cylinder. The periphery of the flange portion 16^b is preferably knurled as shown at 16^c for engagement by the fingers of the operator in order that the head may be readily inserted in

or withdrawn from the cylinder. In order that the cylinder 12 may be held against rotation during the operation of applying or removing the head 16, the upper end of the cylinder is provided 5 with two opposite flat faces 12^a which may be engaged by a wrench or the like. The head 16 is provided at the lower end of the bore of the sleeve-like portion 16^a with an inwardly extending annular flange 16^d which is adapted to interlock 10 with a rubber cup 17 formed of a very flexible quality of rubber or the like. The neck 17^a of this cup is received within the annular flange 16^d and is provided with an outwardly extending flange 17^b which overlies the flange 16^d when the cup is 15 in place. Beneath the head 16, the cup 17 has an outwardly and downwardly flaring skirt 17^c which is adapted to contact with the surface of the uppermost sheet of a pile of sheets 18, resting on a support 19. The cup 17 is retained in place by 20 means comprising a metal sleeve 20 having at its lower end an outwardly flaring flange 20^b which coacts with the under surface of the skirt 17^c of the cup. This sleeve 20 extends upwardly through the neck of the cup concentrically with the sleeve-like portion 16^a of the head and it is externally 25 threaded for engagement by a nut 21 which serves to clamp a washer 22 in position on the upper surface of the cup within the head. The upper end of the nut is provided with a transverse slot 30^a for engagement by a wrench or the like and when the nut is tightened, the sleeve 20 is drawn upwardly so that the cup 17 is clamped firmly in position. With the parts assembled as just described, there is a clearance 23 between the upper 35 end of the sleeve 20 and the lower face of the retaining member 13 and the amount of this clearance represents the extent of upward movement of the cylinder 12 upon the stem 11.

In the operation of this device, a relative movement is effected between the pipe 10 and the pile 40 of sheets 18, with the result that the lower annular end surface of the rubber cup 17 is brought into engagement with the upper surface of the uppermost sheet 18^a. When the rubber cup 17 45 engages this uppermost paper sheet 18^a, the suction acting through the cup from the pipe 10 causes the sheet to adhere to the surface of the cup, thus closing the vacuum channel so that no further air can be drawn in by suction, with the 50 result that the atmospheric pressure on the outside of the cup and on the lower side of the paper sheet then elevates the cup and sheet to the position shown in Fig. 2, with the cylinder 12 sliding upwardly on the stem 11 until the upper end of 55 the head 16 engages the lower end of the hub 13. The paper sheet is then held in position while it is being transferred to a new location by movement of the pipe 10 and the vacuum cup carried thereby. Upon reaching the new location, the 60 suction is cut off from the pipe 10, whereupon the paper sheet is released and allowed to fall in its new location. Of course, a plurality of cups are commonly employed for lifting a single sheet and the suction channels leading to the several 65 cups are relieved of suction at the same time.

In Figs. 4, 5 and 6 of the drawings, there is illustrated a modified form of the invention in which the use of a rubber cup or other resilient member for engaging the paper sheets is avoided. 70 In this form, a pipe 25, connected to a source of suction, is provided with a threaded aperture in which is mounted a depending tubular stem 26 adapted to have a sliding engagement with a cylinder 27. This cylinder is held in place on the

stem 26 by a retaining member 28 having a threaded portion 28^a which engages the internally threaded lower end of the stem and an outwardly extending annular flange 28^b which projects beyond the lower end of the stem and underlies the annular shoulder 27^a which is formed on the inside of the cylinder 27 at the upper end of the enlarged bore thereof which has a sliding engagement with the annular cylindrical surface of the flange 28^b. The cylinder 27 is internally 10 threaded at its lower end for detachable engagement with the externally threaded sleeve portion 29^a of a head 29 which has a flange 29^b extending outwardly beyond the lower end of the cylinder and which is provided at its lower end with an annular flat surface 29^c adapted to coact with the upper surface of the uppermost sheet 30^a of a pile of paper sheets 30 resting upon a support 31. 15

The cylinder 27 normally occupies the position on the stem 26 which is illustrated in Fig. 4. 20 When in this position, the surface 29^c of the head 29 is displaced upwardly from the top of the stack of paper sheets so that the suction acting through the pipe 25 has no effect upon the cylinder 27 or upon the paper sheets. However, when relative movement of the vacuum cup device and the stack of paper sheets takes 25 place to bring the surface 29^c into contact with the upper surface of the upper paper sheet 30^a, the suction line is then sealed against the further intake of the outside air and the paper sheet 30^a is then held in contact with the surface 29^c and the atmospheric pressure then forces the cylinder 27 upwardly until it assumes a position 30 such as that shown in Fig. 5, with the upper sheet 30^a lifted from the stack. The parts are then 35 in readiness to transfer the paper sheet to a new location by movement of the cup or cups to which the sheet adheres. When the new location is reached, the suction is relieved in the pipe 25, 40 whereupon the paper sheet drops in the new location and the cylinder 27 falls by gravity to the original position shown in Fig. 4. It is found that with a device of this simple construction, having a flat annular surface 29^c to engage the 45 paper sheets, a sufficiently air-tight seal may be created to effect the lifting and movement of the paper sheets without the employment of any rubber or other similar sealing means.

When the invention is employed for moving 50 paper sheets which are relatively thin, it may be desirable to overcome any tendency for the paper sheet to be drawn partially into the suction line with the consequent danger of rupturing the portion of the sheet which projects over the vacuum 55 orifice. For use under such circumstances, there has been provided a third form of the invention, which is illustrated partially in Figs. 7 and 8. In this form, the parts are all similar in construction to those illustrated in Figs. 4 and 5, with the lower end of the cylinder 37, corresponding to the cylinder 27, having a threaded engagement with a head 39 provided at its lower end with a flat surface 39^c adapted to coact with the uppermost sheet of a stack of sheets to be moved 60 by the use of the device. In this form, the surface 39^c is a continuous surface of circular outline except for the provision through the central web 39^a thereof of a plurality of small apertures 39^b which permit the suction to act upon the 65 upper surface of the paper while at the same time preventing upward movement thereof within the boundaries of the channel 39^d which is formed through the head 39.

Although three forms of the invention have 70

been shown and described by way of illustration, it will be understood that it may be constructed in various other embodiments within the scope of the appended claims.

5 I claim:

6 1. The combination with a vacuum pipe, of a stem projecting downwardly therefrom, a cylinder slidably mounted on said stem and movable by gravity to its lower position, retaining means

10 carried by said stem at its lower end for engaging said cylinder in said lower position, and a head mounted on the lower end of said cylinder and having an annular flat surface to coact with a paper sheet.

15 2. The combination with a suction pipe, of a hollow stem carried by and communicating with said pipe, a cylinder slidably mounted on said stem, means within said cylinder to limit the downward movement of said cylinder, a head detachably engaging said cylinder and having an internal bore, a flexible vacuum cup having a neck engaging said bore, and clamping means detachably engaging said bore for holding said cup in position on said head.

20 3. The combination with a vacuum pipe, of a stem projecting therefrom, a cylinder mounted on said stem, a head carried by said cylinder and having an internal bore, said head having an inwardly projecting annular flange, a resilient cup carried by said head and having a flange overlying said flange on said head, and relatively adjustable members on opposite sides of said cup for clamping said flanges together.

25 4. The combination with a vacuum pipe, of a stem projecting from said pipe, a cylinder car-

ried by said stem, a head mounted on said cylinder and having an internal bore, a flexible vacuum cup having a neck engaging said bore and having a downwardly and outwardly flaring skirt, a sleeve engaging said bore and having an outwardly flaring flange underlying the skirt of said cup, and means engaging said sleeve in said bore for clamping said cup in position on said head.

5 5. The combination with a vacuum pipe, of a hollow stem projecting from said pipe, a cylinder slidably mounted on said stem, a head detachably mounted on said cylinder and having an internal bore provided with an inwardly projecting annular flange at the lower end thereof, a flexible vacuum cup having a skirt beneath said head and an outwardly projecting flange overlying said first named flange, a tubular member engaging said bore and extending through said cup and having an outwardly flaring flange underlying the skirt of said cup, and a nut threadedly engaging said tubular member within said bore for clamping said cup in position.

10 6. The combination with a vacuum pipe, of a hollow stem projecting from said pipe, a cylinder slidably mounted on said stem and having an inwardly extending annular shoulder, a plug threadedly engaging said stem and having an outwardly extending annular flange adapted to engage said shoulder to limit the movement of said cylinder on said stem, a head detachably engaging said cylinder, and a paper engaging member carried by said head.

ALEXANDER T. KOPPE.
